FISH-LINE SINKER UNIT

Major E. Daves, El Sobrante, Calif.

Application May 17, 1954, Serial No. 30,534

Term of patent 14 years

(Cl. D31—4)

To all whom it may concern:

Be it known that I, Major E. Daves, a citizen of the United States, residing at El Sobrante, county of Contra Costa, State of California, have invented a new, original, and ornamental Design for a Fish-Line Sinker Unit, of which the following is a specification, reference being had to the accompanying drawings, forming a part hereof, wherein,

I claim:

The ornamental design for a fish-line sinker unit, substantially as shown.
